UNITED STATES PATENT OFFICE.

NORRIS ELMORE CLARK, OF PLAINVILLE, CONNECTICUT.

METAL-WORKING.

1,104,477.

Specification of Letters Patent. Patented July 21, 1914.

Application filed November 29, 1912. Serial No. 734,104.

To all whom it may concern:

Be it known that I, NORRIS ELMORE CLARK, a citizen of the United States of America, and residing at Plainville, in the county of 5 Hartford and State of Connecticut, have invented new and useful Improvements in Metal-Working, of which the following is a specification.

My invention relates particularly to a 10 machine for automatically forming reticulated metal sheets.

The main object is to provide a mechanism for expanding slitted or scored sheets of metal uniformly and economically and by 15 means of which longitudinal corrugations of greater or less depth, as desired, may be formed. Sheets of metal are slitted, punched or scored so as to provide a plurality of longitudinal continuous strips connected by 20 expandible sections. This treatment is preferably a simple slitting operation severing the metal in a suitable arrangement but it may be by a punching operation which removes more or less of the stock, or it may 25 be by a scoring operation which removes a part of the thickness of the metal, indenting the metal or weakening it along suitable lines so that the metal may be readily fractured by the subsequent stretching action. 30 For convenience I will refer to such preliminary treatment as scoring, but it will be understood that this case relates solely to the mechanism for handling the scored stock and forming the reticulated product.

35 The mechanism includes a series of punch bars and coacting die bars constructed and arranged so as to subject the scored stock to a corrugating action, bending the strands of the scored sections and forming the open- 40 work or reticulated sections, and then to spread out or flatten the sheet so as to remove the corrugations and bring the reticulated sections all into a common plate. In addition to this action, some or all of the 45 longitudinal strips or unscored portions may be subjected to a corrugating action so as to form stiffening ribs. The shape and size of these ribs will depend upon the particular punches and dies used and their adjustment.

50 At the end of the forming action the ends of the sheet may be trimmed automatically. When treating stock slitted according to my Patent #979,130 I prefer to move the corrugating punch bars longitudinally so as to 55 facilitate the bending of the strands in the

proper direction. This is accomplished automatically in the mechanism herein shown. It should be understood however, that the machine may be employed in treating stock which has been slitted or scored in any suitable arrangement. 60

Important details of improvements will be more fully hereinafter described and set forth in the claims.

Figure 1, is a front elevation of a machine 65 embodying the improvements of my invention. Fig. 2 is a vertical projection of the drive end of the machine. Fig. 3, is a fragmentary detail sectional view showing the method of adjusting the stroke. Fig. 4, is 70 a detail view of an adjustable indicating worm gear. Fig. 5, is a vertical sectional view on the plane of the line X X of Fig. 1 showing the punch and die bars in position ready to receive the scored stock. Fig. 6, 75 is a fragmentary vertical sectional view on the plane of the line X X of Fig. 1 on a larger scale showing the mechanism in position ready to corrugate and illustrating the die locking mechanism. Fig. 7, is a frag- 80 mentary vertical sectional view on the plane of the line Y of Fig. 1 showing the punch and die bars in position at the end of the corrugating action and showing the toggle connections. Fig. 8, is a front view showing the 85 mechanism for releasing the dies and permitting them to close after the completion of the operation. Fig. 9, is a fragmentary detail view showing part of the mechanism for closing the punches. Fig. 10, is a verti- 90 cal sectional view of the same on the plane of the line Z Z of Fig. 9 and showing the mechanism for moving the alternate punch bars longitudinally. Fig. 11, is a detail view showing the part of the mechanism shown 95 in Fig. 10 for causing the return longitudinal movements of the alternate punch bars. Figs. 12 to 16 inclusive are diagrammatic end views of the mechanism showing different stages of the operation. Fig. 12, shows 100 the punch and die bars with the stock in place and before the beginning of the operation. Fig. 13, shows the punch members brought down to engage the stock. Fig. 14 shows the stock corrugated by the downward 105 movement of the alternate vertical punch bars so as to bend the strands and open the meshes. Fig. 15 shows the punch and die bars all moved laterally to spread the sheet and set the sheet and the end cutters oper- 110

ated to trim the ends of the sheet. Fig. 16 shows the punch mechanism raised and the punch bars in their upper retracted position and the finished stock ready to be removed from the die bars. Fig. 17, is a detail fragmentary view of one form of metal lath formed on my improved machine by the method herein set forth. Figs. 18, 19 and 20 are diagrammatic views showing modifications of the punch and die bars for forming a fabric having higher ribs. Fig. 21, is a detail view showing one form of such fabric.

The main lower side frames 1, 1 are supported by the end legs 2, 2 and the center leg 3 and the ends of the side frames are connected by cross members 4, 4. A series of bottom plates such as 5 are supported on the inner flanges of the side frames 1, 1. A series of transverse guide shafts such as 6 and 7 connect the side frames 1, 1 and serve to guide the die members 8, 8 which rest upon the bottom plates 5. The shafts 6, 6 are stationary and the shafts 7, 7 have a limited rotative movement for releasing the dies as will be hereinafter understood.

A series of parallel guide shafts such as 9 have their ends supported in bearing plates 10 which are guided in ways 11 in the inner face of the frames 1, 1, and are vertically movable together with the die bars 12 and 13. Bushings such as 14 are provided for the die bars 12 and 13 to guide them in their lateral movement on the shaft 9. The die bars 8, 8 are also provided with bushings similar to 14 to support them on the shafts 6 and 7. It will be noted that the bushings are practically twice the width of the thickness of the die bars. This affords broad and durable bearing surfaces and assists in maintaining the die bars in their proper vertical positions during their movements. The adjacent die bars are connected to each other by links such as 15, 15 (see Fig. 7) which constitute toggle connections and insure the relative separation of the die bars when the die bars 12 and 13 are forced downwardly, and the upward movement of the die bars 12 and 13 when they are pressed together. Although the die bars are guided on the transverse shafts 6, 7 and 9 and will therefore be maintained parallel to each other as they move laterally, I prefer to provide two sets of these toggle links as shown in the diagram of Fig. 12 at 15 and 15' so as to insure parallel action without binding on the guide shafts. The die bars are pressed toward each other by the die closing levers 16, 16 which are pivoted at 17 and provided with counterweights 18. I also prefer to provide locking devices as shown in Figs. 6 and 8. Some of the shafts 9 are provided with cams such as 19 with recesses 20 at their inner ends to receive spring pressed locking pins 21. The pin 21 is carried by a yoke 22 which is vertically

movable in the outer die bar 13. In the position shown in Fig. 6 the locking pin 21 is arranged in the recess 20 in the shaft 9 and the die bars are all locked together in their closed position. Similar sets of locking pins are provided for the opposite outer die bars 13, 13 as indicated in Fig. 5. At the outer end of the cam 19 is another recess 23 adapted to receive the pin 21 when the die bars are separated in the position indicated in Figs. 15 and 16. The pin 21 is released from the notch 20 when the yoke 22 is pressed downward automatically by the releasing member 24 as will be herein-after understood. The pin 21 is released from the recess 23 by pressing the yoke 22 downward by hand operated mechanism as shown in Fig. 8. The angle bar 25 is supported by arms 26 which are pivoted on shaft 7. Springs 27 press the bar 25 upward. The yoke 22 has a projection 28 which is adapted to come beneath the finger 29 of the arm 26 when the dies are in their opened out position and the pin 21 is in the notch 23. Pressure on the bar 25 rocks the arms 26 and causes the fingers 29 to press down on the projections 28 and move the yokes 22 and pins 21 downward so as to release the die bars and permit the counterweights and levers 16 to draw them together. The center die bar has one or more downwardly projecting pins 30 guided in the bottom plates 5 as shown in Fig. 5 so that the center die bar can simply move up and down while the toggle and parallel connections permit the die bars 8 to move outwardly and the die bars 12 and 13 (except the center die bar 12) to move downward and outward.

At the corners of the machine are four upright posts or columns 35 held to the end leg frames by nuts 36. These columns support the upper side frames 37 and the latter are connected at the ends by the upper end frames 38. On the four columns 35 is guided a vertically movable gate, head or platen. This consists of side frames 40, 40 connected by end frames 41, 41. The side frames 40, 40 are also connected by a top plate or plates 42 similar to the bottom plates 5. The gate carries all the punch bars which are arranged in two series similar to the die bars. The upper punch bars such as 43 and 44 are all guided by shafts 45 which are fixed in the side frames 40, 40 of the gate. The lower punch bars such as 46 alternate with the punch bars 43 and 44 and are carried by a series of shafts such as 47 which are supported by plates 48, 48 which are guided in ways 49 on the inner faces of the side frames 40, 40. The upper center punch bar is secured to the top plate 42 by one or more bolts such as 50 so that it has no lateral movement. The punch bars are connected to each other by toggle links 51, 51

(see Figs. 7 and 12). As before mentioned, in regard to the die bars, these links are preferably arranged in two sets 51', 51' (see Fig. 12) so as to insure parallel action. The upper outer side punch bars 43, 43 are provided with pilot pins 52 which are adapted to fit in holes in the upper outer die bars 13, 13 so that the outer punch and die bars are compelled to move laterally with each other when the pilot pins are entered. The punch and die bars are provided with suitable working faces such as 53, 54 and 55, 56 and 57, 58 shaped according to the shape that it is desired to give the longitudinal members of the product, for instance, corrugated or flat. It is particularly desirable to shape the working faces 57 and 58 so as to corrugate the edges of the sheet longitudinally and grip it more securely. The punch bar member 57 is carried by a number of pins 59 which are guided in the upper outer punch bars 43, 43 and pressed downward for instance by springs such as 60 so that when the members 57 engage the members 58 or the sheet is operated on as shown in Fig. 13, the remainder of the punch mechanism may continue downwardly independently.

In some cases it is desirable to have the lower punch members or their bearing pieces 55 move longitudinally during the corrugating action. This is accomplished by mechanism such as shown in Figs. 9, 10 and 11. The bearing piece 55 fits in a groove 62 in the punch bar 46 and is longitudinally movable being supported by a pin 63 in the slot 64. One or more of the shafts 47 has an arm 65 which fits in a notch 66 in the bearing pieces 55. One end of the notch 66 is formed by a separate plate 67 for the purpose of replacement and taking up wear. The outer ends of the shaft 47 carry cams 68 which embrace the flattened sides of rods 69 which are carried by the stationary brackets 70. The shoulders 69' serve as the upper abutments for the cams 68 and the nut 71 serves as a lower abutment. The ends of the punch bars 46 abut against the lower edge of the plate 72 when the gate is raised. This plate 72 is clamped by bolts 73 to the cross bracket 70 and may be adjusted up or down and held by the set screws 74 so as to vary the upward and downward position of the abutment for the punch bars 46. When the gate 55 is moved downward (as will be hereinafter understood), the lower punch members engage the stock as shown in Fig. 13 and at the same time the cams 68 engage the nuts 71. As the gate continues to move downward and carries the punch members into the position shown in Fig. 14, the cams 68 pressing on the nut 71 cause the shaft 47 to be rotated anti-clockwise as viewed in Fig. 10 and the arm 65 engaging the bearing piece 67 in the slot 66 moves the bearing piece 55

of the punch member 46 longitudinally in the direction of the arrow in Fig. 10. This facilitates uniform action of corrugating the slitted or scored stock but in some cases it may be found unnecessary. When the head 70 is retracted, the cam 68 engages the shoulders 69' on the upward movement and is thus rotated backward and the shaft 47 and arm 65 rotate so as to throw the bearing member 55 toward the left as viewed in Fig. 10. 75

The pulley 75 and its shaft 76 are appropriately geared to the spur gear wheel 77 on the shaft 78. On opposite ends of the shaft 78 are cranks 79, 79 connected by rods 80 to the wrist pins 81 having bearings in the end frames of the gate. It will thus be seen that when the shaft 78 rotates, the gate is vertically reciprocated. The vertical movement of the gate may be started and stopped as desired for instance, by means of a clutch 82 interposed between the gear wheel 77 and the shaft 78 and operated for instance by means of a treadle 83. To counter balance the weight of the gate and 85 the punch members, I have provided a system of counter-weights as shown in Figs. 1 and 2. The weight 84 is carried by the long arm of the lever 85 pivoted at 86. The short arm of the lever is connected by a link 95 87 to the pin 88 carried by the gate. To provide adjustment for the stroke of the punch mechanism I have designed the mechanism shown in Figs. 2, 3 and 4. The wrist pin 81 has secured to it a worm gear 89 and 100 in mesh with this worm gear is a worm 90 carried by the hand wheel 91 for the purpose of rotating the worm gear 89 on its wrist pin shaft 81. The wrist pin 81 is eccentric to the worm gear 89 so that rotation 105 of the worm gear will raise or lower the position of the wrist pin and thus vary the position of the gate and the action of the mechanism. For the purpose of clamping the adjusting worm 90 and the worm gear 110 89 I have split the head of the connecting rod 80 as at 92 and provided a take-up or clamp-bolt 93 (see Fig. 3). In order that both ends of the gate may be adjusted properly to the same extent, I have provided an 115 indicating device. This consists of a scale 94 on the worm gear 89 and a sight opening 95 in the end yoke of the gate (see Figs. 2 and 4). When the hand wheel 91 and the worm gear 89 are rotated, the scale reading 120 is taken through the sight opening and the same adjustment may be effected on the opposite end of the machine.

Cutter mechanism is provided at opposite ends of the machine for cutting off or trimming the ends of the sheet after the corrugating and spreading action. This consists of cutters 97 and 98 at opposite ends, the upper cutter being movable with the gate and brought into co-action with the 130

lower cutter at the lower end of the stroke. The cutters may be omitted however if trimming is not desired.

The operation is substantially as follows.

- 5 The mechanism being in the position shown in Figs. 1, 2, 5 and 12, a sheet 100 of metal slitted or scored according to the desired pattern is inserted on top of the die bars. By depressing the pedal 83 the clutch 82
- 10 throws the shaft 78 into operation and the cranks 79 on opposite ends draw downward the connecting rods 80 at the opposite ends of the gate. The parts then proceed downward into the position shown in Fig. 13.
- 15 The side bars securely grip the un-slitted margins of the sheet and may corrugate the margins so as to facilitate the gripping action. The continued downward movement of the gate brings the parts into the position
- 20 shown in Fig. 14, wherein the slitted or scored portions are longitudinally corrugated along their central portions so as to open the meshes. The first part of the downward movement of the gate inserts the
- 25 pilot pins 52, 52 into the lower side die bars just prior to the position of Fig. 13, and the release pins 24 engage the upper ends of the yokes 22 and thus disengage or throw out the latch pins 21 when the parts are in the
- 30 position of Fig. 14. The continued downward movement of the gate brings considerable pressure to bear from the punch bars to the die bars and on the metal stock between them, the upper punch bars pressing
- 35 upon the stock on the upper die bars and the lower punch bars pressing against the stock on the lower die bars. This causes a simultaneous leveling and spreading action of the punch and die bars so that the corrugated
- 40 sheet is spread out into the position shown in Fig. 15 and the locking pin 20 snaps into the outer recess 23 thus locking the die bars in the position shown in Figs. 15 and 16. The last downward movement of the gate
- 45 causes the upper cutters 97 to co-act with the lower cutters 98 and shear off the ends of the fabric. Continued rotation of the shaft 78 raises the gate and the punch bars and the pilot pins 72 are released. When
- 50 the ends of the lower punch bars 46 engage the lower edges of the plates 72 the upward movement of the lower punch bars is arrested and continued upward movement of the gate by reason of the toggle connection between the two sets of punch bars draws all the punch bars together in a lateral direction and they take up the position shown in Figs. 5 and 16. When the finished sheet 101 is removed, the hand plate 25 is depressed
- 55 and the yoke 22 pressed down (see Fig. 8) so as to release the pin 21 from the recess 23. The die bars being then released are drawn together into the position shown in Figs. 5, 6, 7 and 12 by the action of the counter-
- 60 weights 18 and the die closing levers 16
- 65

which give an inward and upward pressure on the upper die bars. By this mechanism and method of operation the longitudinal tension members of the fabric may be flat or corrugated as desired according to the shape 70 of the bearing faces of the punch and die members. Fig. 17 shows one form of fabric having all of the tension members longitudinally corrugated, the corrugations of alternate members facing in opposite directions. 75 Fig. 21 shows another form of fabric made according to my invention and Figs. 18, 19 and 20 diagrammatically illustrate the steps in the manufacture and some details of construction. In this form of fabric there are 80 parallel longitudinal strips 103 which are folded or bent so as to project materially from the plane of the reticulated portion of the fabric. The reticulated portion preferably consists of two sections of mesh work 85 united midway between the strips 103 preferably by a strip 104. The blank sheet of stock, scored or slitted so as to render certain portions extensible, is laid upon the die bars as previously described. The un-scored 90 portions are supported on the die bars 106 and 107 and the un-scored margins are engaged by the punch bars 108. The bearing faces 109 of the intermediate punch bars 110 are brought to bear upon the center lines of the scored sections of the stock midway between the die bars 106 and 107 and the stock is corrugated as shown in Fig. 19. The continued downward movement of the punch bars forces the un-scored metal into the 95 grooves of the die bars 106 and 107 and at the same time separates the punch and die bars laterally as shown in Fig. 20. The punch members 109 are backed up by springs indicated at 111. These springs are strong 100 enough to permit the bearing pieces 109 to perform their function of corrugating as shown in Fig. 19, but not strong enough to prevent the movement into the position of Fig. 20 by the continued downward action 105 of the gate at the end of the downward stroke, the springs being compressed. By a suitable proportion and adjustment of the mechanism, the final spreading action into the position shown in Figs. 15 and 20 may 110 be caused to set the metal so as to make the sheet perfectly flat and prevent it from buckling or kinking.

It will be obvious that this machine may be used for expanding stock which has been previously grooved or ribbed along its un-slitted portions. It will also be understood that the mechanism may be employed to spread the stock laterally which has previously been corrugated along its slitted portion by other mechanism. I wish it also understood that I contemplate that many changes and substitutions may be made in the mechanism and parts omitted or others added without departing from the spirit and 115 120 125 130

scope of my invention and that the terms employed in the claims are terms of description rather than of limitation except so far as required by the state of the art.

5. What I claim is:—

1. In a metal working machine, two series of vertically and laterally movable punch bars, coöperating die bars and means for bringing one series of the punch bars into operation in advance of the other series upon slitted stock to corrugate the same and form corrugated mesh work and means for separating the bars laterally for spreading out the corrugated portions of the reticulated sheet and setting it without closing the mesh work. 70
2. In a metal working machine, a series of vertically and laterally movable punch bars, coöperating die bars and means for bringing the punch bars into operation upon slitted stock to corrugate the same and form mesh work, means for separating the bars laterally for spreading out the reticulated sheet and means for automatically locking one set of bars in their laterally separated position. 80
3. In a metal working machine, a series of vertically and laterally movable punch bars, coöperating die bars and means for bringing the punch bars into operation upon slitted stock to corrugate the same and form mesh work, means for separating the bars laterally for spreading out the reticulated sheet, means for automatically locking one set of bars in their laterally separated position and manually controlled means for releasing said locking means. 85
4. In a metal working machine, a series of vertically and laterally movable punch bars, coöperating die bars and means for bringing the punch bars into operation upon slitted stock to corrugate the same and form mesh work, means for separating the bars laterally for spreading out the reticulated sheet and means for moving alternate bars of one set of bars longitudinally. 100
5. In a metal working machine, a series of punch bars and a series of die bars corresponding thereto, parallel motion links connecting the punch bars, parallel motion links connecting the die bars and means for bringing one set of bars into operation in conjunction with slitted stock to corrugate and spread the same. 105
6. In a metal working machine, a set of die bars arranged in two series, horizontal guide shafts, one set of die bars being laterally movable thereon and vertically movable horizontal guide shafts carrying the other set of die bars, connecting links between the die bars and punch bars for coöperating with said die bars for corrugating and spreading the sheet substantially as described. 110
7. In a metal working machine, a set of die bars arranged in two series, horizontal
- guide shafts, one set of die bars being laterally movable thereon and vertically movable horizontal guide shafts carrying the other set of die bars, connecting links between the die bars, punch bars for coöperating with said die bars for corrugating and spreading the sheet substantially as described and means for locking the die bars in their laterally separated position. 75
8. In a metal working machine, a set of die bars arranged in two series, horizontal guide shafts, one set of die bars being laterally movable thereon and vertically movable horizontal guide shafts carrying the other set of die bars, connecting links between the die bars, punch bars for coöperating with said die bars for corrugating and spreading the sheet substantially as described, means for locking the die bars in their laterally separated position and means for manually releasing the same. 85
9. In a metal working machine, a set of die bars arranged in two series, horizontal guide shafts, one set of die bars being laterally movable thereon and vertically movable horizontal guide shafts carrying the other set of die bars, connecting links between the die bars, punch bars for coöperating with said die bars for corrugating and spreading the sheet substantially as described, means for locking the die bars in their laterally separated position and means for pressing said die bars together. 90
10. In a metal working machine, a set of die bars arranged in two series, horizontal guide shafts, one set of die bars being laterally movable thereon and vertically movable horizontal guide shafts carrying the other set of die bars, connecting links between the die bars, punch bars for coöperating with said die bars for corrugating and spreading the sheet substantially as described and means for locking the die bars together. 105
11. In a metal working machine, a set of die bars arranged in two series, horizontal guide shafts, one set of die bars being laterally movable thereon and vertically movable horizontal guide shafts carrying the other set of die bars, connecting links between the die bars, punch bars for coöperating with said die bars for corrugating and spreading the sheet substantially as described, means for locking the die bars together and means operating with the punch bars for releasing said locking mechanism. 115
12. In a metal working machine, two sets of punch bars, two sets of die bars, said punch bars being vertically movable and all of said punch bars except the central punch bar being laterally movable, some of said punch bars having a greater vertical movement than the others. 125
13. In a metal working machine, two sets of punch bars, two sets of die bars, said

5 punch bars being vertically movable and all of said punch bars except one punch bar being laterally movable, some of said punch bars having a greater vertical movement than the others and means for interlocking the punch bars with the die bars for causing them to separate laterally at the same time.

14. In a metal working machine, two sets 10 of punch bars, two sets of die bars, said punch bars being vertically movable and all of said punch bars except one punch bar being laterally movable, some of said punch bars having a greater vertical movement than the others and means connecting the punch bars for causing them to move laterally and be maintained parallel while moving vertically.

15. In a metal working machine, two 20 series of die bars, the central die bar and die bars alternating therewith being vertically movable, the die bar on each side of the central bar being laterally movable and punch bars coöperating with said die bars, the central punch bar being vertically movable and the other punch bars being laterally and vertically movable.

16. In a metal working machine, two sets 30 of die bars, the central die bar and die bars alternating therewith being vertically movable, the die bar on each side of the central bar being laterally movable and punch bars coöperating with said die bars, the central punch bar being vertically movable and the other punch bars being laterally and vertically movable and means for interlocking said punch and die bars.

17. In a metal working machine, two sets 40 of die bars, the central die bar and die bars alternating therewith being vertically movable, the die bars on each side of the central bar being laterally movable and punch bars coöperating with said die bars, the central punch bar being vertically movable and the other punch bars being laterally and vertically movable, means for interlocking said punch and die bars and means for releasing the interlocking means.

18. In a metal working machine, two sets 50 of die bars, the central die bar and die bars alternating therewith being vertically movable, the die bar on each side of the central bar being laterally movable and punch bars coöperating with said die bars, the central punch bar being vertically movable and the other punch bars being laterally and vertically movable, means for interlocking said punch and die bars and means for causing the punch bars and die bars to move vertically and laterally together and maintaining the punch bars in parallel planes.

19. In a metal working machine, two 60 series of bars, one series being vertically movable and both series being laterally movable, guide shafts for both series of bars

and parallel motion links connecting said series of bars.

20. In a metal working machine, two 70 series of bars, one series being vertically movable and both series being laterally movable, guide shafts for both series of bars, parallel motion links connecting said series of bars and means for locking the bars together.

21. In a metal working machine, two 75 series of bars, one series being vertically movable and both series being laterally movable, guide shafts for both series of bars, parallel motion links connecting said series of bars, means for locking the bars together 80 and means for releasing said locking means.

22. In a metal working machine, two 85 series of bars, one series being vertically movable and both series being laterally movable, guide shafts for both series of bars, parallel motion links connecting said series of bars and means for locking said bars in position when laterally separated.

23. In a metal working machine, two 90 series of bars, one series being vertically movable and both series being laterally movable, guide shafts for both series of bars, parallel motion links connecting said series of bars, means for locking said bars in position when laterally separated and means for manually 95 releasing said locking means.

24. In a metal working machine, two 100 series of bars, means for moving one of said series of bars vertically, means for separating all of said bars laterally and means for longitudinally moving one of said series of bars.

25. In a metal working machine, two 105 series of punch bars, a series of die bars co-operating with one series of said punch bars to hold unslotted portions of slotted stock, means for bringing the other series of punch bars into operation to form deep corrugations along the center lines of the slotted portions and form the open mesh and means for laterally separating the punch bars for spreading the stock and bringing the corrugated portions into a common plane.

26. In a metal working machine, two 110 series of punch bars, two sets of die bars, means for moving said punch bars so as to corrugate the slotted portions of the stock, means for separating said bars for spreading the stock and means at the same time for corrugating the unslotted portions of the 120 stock.

27. In a metal working machine, two 125 series of punch bars, two series of die bars and means for moving said punch bars vertically to corrugate the slotted stock and to form shallow corrugations in un-slotted portions of the stock and means for separating said bars for spreading said stock.

28. In a metal working machine, two 130 series of punch bars, two series of die bars,

means for moving some of said punch bars for corrugating slotted portions of the stock, means for moving other punch bars for corrugating unslotted portions of the stock and means for separating said bars for spreading the corrugated slotted portions.

29. In a metal working machine, vertical movable punch bars and die bars for coacting therewith, means for interlocking the punch bars and die bars, means for locking the die bars together in the first part of the operation of the machine, means for releasing said locking mechanism, and means for spreading said punch bars and die bars 15 apart laterally when said locking means is released.

30. In a metal working machine, vertical movable punch bars and die bars for coacting therewith, means for interlocking the punch bars and die bars, means for locking the die bars together in the first part of the operation of the machine, means for releasing said locking mechanism, means for spreading said punch bars and die bars apart 25 laterally when said locking means is released and means for locking the die bars in their laterally separated position.

31. In a metal working machine, vertical movable punch bars and die bars for coacting therewith, means for interlocking the punch bars and die bars, means for locking the die bars together in the first part of the operation of the machine, means for releasing said locking mechanism, means for spreading said punch bars and die bars apart laterally when said locking means is released, means for locking the die bars in their laterally separated position and means for retracting the punch bars.

32. In a metal working machine, a series of punch bars, a series of die bars and means for vertically reciprocating the punch bars including adjustable connecting rods at opposite ends of the punch bars, adjustable eccentrics with indicating dials and hand operable means for rotating said eccentrics.

33. In a metal working machine, two series of die bars, a bed supporting one series of die bars, vertically movable shafts supporting the other series of die bars, two series of vertically movable punch bars for coacting with said die bars and means for forcing some of said punch bars and die bars apart laterally.

34. In a metal working machine, two series of die bars, one series being laterally movable, the other series being vertically movable, some of said second series being laterally movable, a vertically movable gate including a top bar, punch bars carried by said gate and arranged in two series, one series abutting against the under side of said top bar and some of said series being laterally movable and the other series of punch bars being laterally movable and also

vertically movable relative to the first mentioned series of punch bars.

35. In a metal working machine, two series of vertically movable punch bars, die bars coacting therewith, connecting links between the adjacent bars and a stop plate engaged by one series of punch bars for limiting their upward movement and causing said punch bars to close together as the other series of punch bars moves vertically.

36. In a metal working machine, two series of vertically movable punch bars, die bars coacting therewith, connecting links between the adjacent bars and a stop plate engaged by one series of punch bars for limiting their upward movement and causing said punch bars to close together as the other series of punch bars moves vertically and means for adjusting said stop plate.

37. In a metal working machine, two series of die bars, one series being laterally movable and some of the die bars of the other series being vertically and laterally movable and means pressing upwardly and toward the center on the outer die bars for forcing them together and means of connection between said die bars for causing them to move in parallel planes and punch bars coöperating therewith.

38. In a machine for expanding sheet metal the combination of pedestals, a lower frame carried thereby, a plurality of transversely movable die bars extending longitudinally of said frame, means tending to press said die bars toward each other, corner posts supported by said pedestals, an upper frame connecting the upper ends of said posts, a vertically movable gate guided on said posts, a plurality of transversely movable punch bars carried by said gate and extending longitudinally thereof for coöperating with said die bars, a main shaft extending beneath the lower frame, cranks on its opposite ends, rods connecting said cranks with said gate for moving said gate vertically and means for causing the respective punch bars and die bars to separate laterally when said gate is depressed.

39. In a machine for expanding sheet metal, a lower frame, guide shafts extending transversely thereof, bushings mounted on said shafts, die bars mounted on said bushings, means for holding said die bars spaced apart from each other, punch bars for coöperating with stock supported on said die bars and means for moving the punch bars and die bars laterally to spread the stock.

40. In a machine for expanding sheet metal, a plurality of transverse guide shafts, bushings supported on said shafts, die bars mounted on said bushings, other die bars mounted between said first mentioned die

- bars, a support for said other die bars and punch bars for coöperating with all of said die bars and means for operating said punch and die bars for spreading stock.
5. 41. In a machine for expanding sheet metal, bottom plates, a series of die bars supported thereon, a second series of die bars, supporting shafts for said second series of die bars with means for connecting the bars of the two series to cause them to have proportionate lateral movements and punch bars coöperating with all of said die bars.
10. 42. In a machine for expanding sheet metal, an upper frame, transverse guide shafts carried thereby, a series of punch bars supported on said guide shafts, a second series of punch bars, guide shafts for said second series of punch bars, means for connecting the punch bars of the two series for causing them to have proportionate limited movements and die bars coöperating with said punch bars.
15. 43. In a metal working machine, a series of vertically and laterally movable punch bars, coöperating die bars and means for bringing the punch bars into operation upon slitted stock to corrugate the same and form mesh work and means for separating the bars laterally for spreading out the reticulated sheet and cutters for trimming the ends of the sheet.
20. 44. In a metal working machine, a series of vertically and laterally movable punch bars, coöperating die bars and means for bringing the punch bars into operation upon slitted stock to corrugate the same and form mesh work, means for separating the bars laterally for spreading out the reticulated sheet and means for moving alternate bars of one set of bars longitudinally and cutters for trimming the ends of the sheet.
25. 45. In a metal working machine, two sets of punch bars, two sets of die bars, said punch bars being vertically movable and all of said punch bars except the central punch bar being laterally movable, some of said punch bars having a greater vertical movement than the others and cutters for trimming the ends of the sheet.
30. 46. In a metal working machine, two series of die bars, the central die bar and die bars alternating therewith being vertically movable, the die bar on each side of the central bar being laterally movable and punch bars coöperating with said die bars, the central punch bar being vertically movable and the other punch bars being laterally and vertically movable and cutters for trimming the ends of the sheet.
35. 47. In a metal working machine, two series of bars, one series being vertically movable and both series being laterally movable, guide shafts for both series of bars and parallel motion links connecting said series of
- bars and cutters for trimming the ends of the sheet.
48. In a metal working machine, two series of punch bars, two sets of die bars, means for moving said punch bars so as to corrugate the slitted portions of the stock and means for separating said bars for spreading the reticulated stock and cutters for trimming the ends of the sheet.
70. 49. In a metal working machine, two series of punch bars, two sets of die bars, means for moving said punch bars so as to corrugate the slitted portions of the stock, means for separating said bars for spreading the stock and means at the same time for corrugating the unslitted portions of the stock and cutters for trimming the ends of the sheet.
75. 50. In a metal working machine, two series of punch bars, two series of die bars and means for moving said punch bars vertically to corrugate the slitted stock and to form shallow corrugations in unslitted portions of the stock and means for separating said bars for spreading said stock and cutters for trimming the ends of the sheet.
80. 51. In a metal working machine, two series of punch bars, two series of die bars, means for moving some of said punch bars for corrugating slitted portions of the stock, means for moving other punch bars for corrugating unslitted portions of the stock and means for separating said bars for spreading the corrugated slitted portions and cutters for trimming the ends of the sheet.
85. 52. In a metal working machine, vertical movable punch bars and die bars for coacting therewith, means for interlocking the punch bars and die bars, means for locking the die bars together in the first part of the operation of the machine, means for releasing said locking mechanism and means for spreading said punch bars and die bars apart laterally when said locking means is released and cutters for trimming the ends of the sheet.
90. 53. In a metal working machine, a main frame, two series of die bars carried thereby and vertically and laterally separable, a cutter carried by said frame across the end of said die bars, a reciprocating gate, two series of punch bars carried by said gate and vertically and laterally separable, and a cutter carried by said gate to coöperate with said first mentioned cutter.
95. 54. In a metal working machine, bars for gripping the edges of a slitted sheet, vertically movable bars for holding unslitted intermediate portions of the sheet, bars for corrugating and opening the slitted portions of the sheet and means for separating all of said bars so as to spread out the corrugated slitted portions.
100. 55. In a metal working machine, bars for gripping the edges of a slitted sheet, vertically movable bars for holding unslitted in-
105. 110. 115. 120. 125. 130.

termediate portions of the sheet, bars for corrugating and opening the slotted portions of the sheet, means for separating all of said bars so as to spread out the corrugated slotted 5 portions and cutters for trimming the ends of the sheet.

56. In a metal working machine, means for expanding a slotted sheet and cutters for transversely trimming the ends of the expanded sheet and means for automatically 10 and sequentially operating the expanding means and the cutters.

57. In a metal working machine, punch and die bars adapted to hold between them a corrugated expanded metal fabric, means 15 for spreading said bars laterally to bring the expanded portions into a common plane and means engaging the expanded portions for holding them while the fabric is being spread 20 out.

58. In a machine for expanding sheet metal, a set of die bars normally spaced apart from each other and adapted to support the ribs of a corrugated meshwork, a 25 set of punch bars adapted to engage the ribs of meshwork supported on said die bars, means for moving said punch bars vertically, means for moving said punch bars and said die bars laterally to spread the 30 corrugated meshwork and means arranged between the bars of one set of said sets of bars for coöperating with the corrugated meshwork during the spreading action and assisting it to its proper spread position.

59. In a machine for expanding sheet metal, a set of die bars normally spaced apart from each other and adapted to support the ribs of a corrugated meshwork, a plurality of punch bars adapted to engage 40 the ribs of said meshwork on said die bars, other punch bars for engaging the meshwork between said die bars and means for separating said punch bars and said die bars laterally for spreading the stock.

60. In a machine for expanding sheet metal, a plurality of die bars, pivoted, counter-weighted die closing levers, punch bars for coöperating with said die bars, means 45 for operating said punch and die bars to spread the stock, means for locking the die

bars in their spread position and means for releasing said locking means and permitting said levers to close said die bars.

61. In a machine for expanding sheet metal, a set of die bars for supporting the ribs of a sheet, a set of punch bars for engaging ribs supported on said die bars, means for moving said punch bars downwardly, means connecting said die bars for causing them to move downwardly and to 55 separate laterally when pressure is applied to them by said punch bars, whereby the stock is automatically spread by the operation of the pressure of the punch bars.

62. In a machine for expanding sheet metal, a set of die bars for supporting the ribs of the stock, a set of punch bars for engaging the ribs supported on said die bars, other punch bars between the bars of said set of punch bars, abutments for said 60 other punch bars, means of connection between all of said punch bars, whereby when said punch bars are depressed certain of said punch bars engage said abutments and automatically spread said punch bars laterally when pressure is applied upon them. 75

63. In a machine for expanding sheet metal, a plurality of die bars for supporting the ribs of the stock, a plurality of punch bars for coöperating with the ribs supported on said die bars, means for separating the punch bars and the die bars laterally to spread the stock, means for automatically locking the die bars in their spread position while the punch bars are being retracted, 80 means for releasing said die bars and means for closing said die bars when released.

64. In a machine for expanding sheet metal, a set of die bars, means for locking them in their closed position, a vertically movable gate, punch bars carried thereby for coöperating with said die bars, means for depressing said gate and punch bars and means carried by said gate for releasing 85 said locking means when said gate is depressed.

NORRIS ELMORE CLARK.
